MEANS FOR DISTRIBUTING VISCOUS SUBSTANCES ON FALLING FILM EVAPORATORS

Konrad Brunk, Leverkusen, Germany, assignor to Farbenfabriken Bayer Aktiengesellschaft, Leverkusen, Germany, a corporation of Germany

Filed Apr. 1, 1958, Ser. No. 725,743

Claims priority, application Germany Apr. 5, 1957

6 Claims. (Cl. 159—6)

The distributors hitherto usually employed in thin-layer evaporators consist of brushes, wiper blades, doctors or scrapers, which are arranged on a shaft rotating in the evaporator body and slide on the inside wall of the latter or sweep past close alongside the same. The fine dust being formed with rubbing or sliding distributor elements enters into the substance being processed and contaminates the latter, this being undesirable in many cases. When highly viscous pasty or like masses are introduced into the thin-layer evaporator, the aforementioned distributor devices which have so far been employed can only be used under certain circumstances, since it is frequently not possible to obtain with them a uniform distribution of these viscous masses on the inside wall of the evaporator.

It has now been found that the said disadvantages are avoided if the distributor device consists, in accordance with the invention, of at least one roller which is rotatably mounted in cross-members connected to the shaft and in addition is preferably movable radially in slots of the cross-members, so that it rolls on the inside wall of the evaporator chamber owing to centrifugal force as the shaft rotates and thus distributes the product to be processed. Since the roller rotates, the rubbing action is negligibly small, so that contamination of the substance being treated is practically avoided. Finally, the roller can also be so arranged, for example by stop devices, that it is stopped at a certain distance from the inside wall.

By using such rollers, not only thin liquid but especially also very viscous masses can be satisfactorily rolled out on the inside wall to provide a thin film. The use of the distributor according to the invention also provides an increase in the evaporator surface and thus an increase in the evaporator output, since as the rollers rotate, some of the substance to be treated is also taken up on the surface of the said rollers. In order fully to utilize this increase in surface, the rollers are provided with an internal heating system. In order in certain cases to obtain a positive or negative slipping of their surfaces on the inside wall, the rollers are provided with an independent driving means. In order to allow the rollers to roll on the wall of the container with a pressure exceeding the centrifugal force, they are provided with a supplementary pressure device, for example a resilient pressure device.

The construction of the distributor device can be varied in many ways, depending on the number and diameter of the rollers and also the arrangement and shape thereof. For example the rollers can be made of the same length as the length of the evaporator which is to be swept over.

The rollers, especially when they are of small diameter, can be mounted not only at the top and bottom, but once or several places along their length.

Several separate rollers of shorter length can be arranged in series or adjacent one another.

The rollers can be of conical shape instead of being of cylindrical form.

The rollers can be shaped, for example provided with spiral threads.

In order to produce a thrust action in a downward di-

2

rection on the product to be treated, the rollers can be arranged with their central axis inclined to the central axis of the evaporator and they are then given for example an ellipsoid form.

5 Embodiments of the device according to the invention are shown diagrammatically and by way of example in the drawing. FIGURE 1 is a longitudinal section through an evaporator body having distributor rollers for thinly liquid and thickly liquid substances. FIGURE 2 is a cross-section through this apparatus, FIGURE 3 is a longitudinal section through an evaporator with a distributor device which is particularly suitable for highly viscous pastry substances. FIGURE 4 shows a constructional example of an internally heated roller, FIGURE 5 shows 10 a roller with its own driving means, FIGURE 6 shows a roller with a spring pressure device and FIGURES 7 and 15 8 show a distributor device having rollers arranged inclined in relation to the evaporator axis.

Referring to the constructional example illustrated in 20 FIGURES 1 and 2, the reference 1 represents the evaporator chamber with the heating jacket 2. Arranged in the evaporator 1 is the driving shaft 3 with the cross-members 4 fixed thereon, the rollers 6 being rotatably mounted by means of their journals 7 in the slots 5 of 25 said cross-members. The inlet tube for the material to be treated is indicated at 8. As the shaft 3 and thus the cross-members 4 rotate, the rotatably mounted distributor rollers 6 are urged by the centrifugal force on to the inside wall of the evaporator 1 and on to the substance supplied through the pipe 8 and flowing down on said wall, 30 the rollers rolling on the said substance and distributing it uniformly on the wall surface by rolling it out in a thin layer on the said wall. The arrangement shown in FIGURE 3, which is more especially suitable for distributing viscous substances which no longer are able to comply with the force of gravity owing to their adhesion power, also consists of the evaporator casing 1 with the heating jacket 2, the cross-members 4 of the shaft 3, the 35 rotatably arranged rollers 6 and a supply pipe 8 for the material. In this case, however, a propeller member 9 formed of a spiral two-thread worm of flat sheet metal blading is additionally arranged on the shaft 3 so that about two thirds of the length of the worm is above and one third is below the supply pipe 8 and that the lower 40 ends of the worm threads extend to between the upper ends of the distributor rollers 6. This propeller member 9 urges the material downwardly on the evaporator surface and away from outlet 10 and prevents any doughy viscous product forced into the apparatus from damming 45 up in the space above the rollers. The evaporator casing 1 is equipped with an outlet pipe 10 for the distillate vapours and an outlet pipe 11 for the residue. The shaft 3 is guided through the cover 12 of the evaporator casing 1 and carries at its end a driving pulley 13. The 50 passage for the shaft through the cover 12 is sealed by means of a stuffing box. According to FIGURE 4, the roller is made hollow and is rotatably mounted on the hollow angle piece 16 of the hollow cross-member 17. Fixed to the journal of the angle piece 16 is a heating element 18 which serves to heat the interior of the roller 55 15. The leads 19 for supplying the heating current are led outwardly through the hollow part of the shaft 20 to slip rings.

FIGURE 5 shows a distributor roller with a separate 60 or individual driving means. In this figure, 21 represents the internal wall of the evaporator, 22 the supply opening for the product to be treated, 23 the discharge pipe for the distillate vapours, 24 the main driving shaft, 25 an internally toothed crown wheel which is fixed to the collar 26, 27 is a bushing which is connected fast to the shaft 24 and which is provided at the upper end with a disc 27a and at the bottom end with a cross-member 27b forked

at its ends, 28 is a gear wheel mounted in the disc 27a and having a pinion 28a which meshes with the crown wheel 25; 29 is an intermediate pinion mounted in the disc 27a, 30 is the driving pinion for the roller and mounted in the disc 27a, 31 is the roller with its upper bearing journal 31a, 33 are blocks sliding in the forks of the cross-member providing bearings for the journals of the rollers 31, and 34, 35 and 36 are articulated shaft connections between the pinion 30 and the roller journal 31a.

When the main driving shaft 24 rotates, the pinion 28a rolls on the crown wheel 25, from which the rotational movement is transmitted through the gear wheel 28 and the pinions 29 and 30 by means of the articulated shaft connections 34, 35, 36 to the rollers 31. Depending on the transmission ratio chosen for the gearing, the peripheral speed of the roller is equal to, larger than or smaller than the peripheral speed of a point around the shaft 24 at the distance of half the diameter of the evaporator space, i.e. the surface of the roller either has no slip, or a positive or negative slip, relatively to the inside wall of the evaporator. A displacement of the rollers, which is necessary when distributing the product which is to be treated, is obtained by mounting the rollers in blocks sliding in the forks of the cross-members.

According to FIGURE 6, the rollers 38 rolling on the wall of the container 37 have their ends mounted in sliding members 39 and are forced by means of the leaf springs 40 against the wall 37 by means of the sliding blocks 39 displaceable in the cross-members 41.

A distributor device having rollers arranged at an inclination to the means axis is shown in FIGURES 7 and 8 and therefore having an elliptical profile.

In these figures, 42 is the driving shaft, 43 is the upper and lower cross-members connected fast to the shaft 42, 45 are the convex inclined rollers movably mounted in the forked ends of the cross-members, 46 is the wall of the evaporator space and 47 is the supply pipe for the product.

As the shaft rotates in the direction indicated, the product to be processed is given a downward thrust by the rotating inclined rollers and this assists the action of the force of gravity.

I claim:

1. An evaporator comprising an evaporator chamber

having an inlet having material to be treated and an outlet for withdrawal of vapor, roller means below said inlet and adapted to spread said material thinly on the inner wall of said chamber, and propeller means within said chamber extending from said inlet below said roller means to advance such material thereto.

2. An evaporator as set forth in claim 1 in which said roller means includes at least one roller urged by centrifugal force in the direction of said chamber inner wall.

3. An evaporator as set forth in claim 1 in which said propeller means includes spiral blading adjacent the inner wall of said chamber.

4. An evaporator as set forth in claim 1 in which said propeller and roller means are rotatable about the center of said chamber.

5. An evaporator as set forth in claim 4 in which said chamber is provided with a central vertical rotatable shaft and said propeller and roller means are adapted to be rotated in said chamber by said shaft.

6. An evaporator comprising a cylindrical evaporator chamber having an inlet for material to be treated and an outlet for withdrawal of vapor, a central vertical shaft, a plurality of rollers mounted for rotation upon and by said shaft, and adapted to be urged by centrifugal force toward the inner wall of said chamber and to spread said material thinly thereon, spiral blading carried by said shaft and rotatable therewith, adjacent the inner wall of said chamber and extending above said inlet substantially two-thirds of the overall length of the blading and above said inlet to propel said material from the inlet to said rollers.

CERTIFICATE OF CORRECTION

Patent No. 3,058,516

October 16, 1962

Konrad Brunk

It is hereby certified that error appears in the above numbered patent requiring correction and that the said Letters Patent should read as corrected below.

Column 2, line 13, for "pastry" read -- pasty --;
column 4, line 37, for "1,284,974 Du Pont" read
-- 1,284,074 du Pont --.

Signed and sealed this 7th day of May 1963.
